UNITED STATES PATENT OFFICE

2,222,017

FEEDING MECHANISM FOR SEWING MACHINES

Rudolph Becker, North Plainfield, N. J., assignor to The Singer Manufacturing Company, Elizabeth, N. J., a corporation of New Jersey

Original application June 2, 1938, Serial No. 211,345. Divided and this application July 26, 1939, Serial No. 286,546

10 Claims. (Cl. 112—215)

This application is a division of my application Serial No. 211,345, filed June 2, 1938.

This invention relates to sewing machines and more particularly to improved mechanism for effecting movement of the work through the machine during the operation thereof.

An object of the invention is to provide an improved and simplified feeding mechanism for sewing machines, which is easy running and quiet in operation; in which vibration is reduced to a minimum; which is capable of being embodied in a substantially closed casing and therein subjected to continuous and automatic lubrication; and in which the work-engaging face of the feed-dog is maintained parallel with the work-supporting surface of the throat-plate during the entire work-advancing stroke of the feed-dog.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings, Figure 1 is a front elevation, partly in section, of a sewing machine embodying the present invention.

Fig. 2 is a right end view of the machine shown in Fig. 1 with the hand-wheel and an end cover-plate removed.

Fig. 3 is a horizontal sectional view taken substantially on the line 3—3 of Fig. 1.

Fig. 4 is an enlarged vertical sectional view substantially on the line 4—4 of Fig. 3.

Fig. 5 is a transverse vertical sectional view substantially on the line 5—5 of Fig. 3.

Fig. 6 is a detail vertical sectional view substantially on the line 6—6 of Fig. 3.

Referring more specifically to the drawings, the invention is disclosed as embodied in a sewing machine comprising a base 1, standard 2, overhanging arm 3 and head 4. A main driving

shaft 5 is journaled lengthwise of the arm and carries at its rear end a combined belt- and hand-wheel 6. At its forward end, the shaft 5 actuates, through suitable mechanism designated generally as 7, a reciprocatory needle-bar 8 which

is mounted in the head 4 and carries, at its lower end, an eye-pointed needle 9. Also mounted in the head 4 is a spring-pressed presser-bar 10 within the bifurcated lower end of which is secured, as by a clamp-screw 11, the upright

shank 12^a of a presser-foot 12. To enable the

presser-foot to be tilted relative to its supporting bar 11, and to maintain the foot in its tilted position, the foot carries opposed stop-screws 13 and 14 the heads of which are adapted to engage the opposite sides of the lower end 10^a of the presser-bar. By releasing the clamp-screw 11 and adjusting the stop-screws 13 and 14 the foot may be tilted relative to the bar 10 to cause either the toe-portion or the heel-portion to bear more heavily upon the work. After the desired adjustment has been made, the foot may be secured to the presser-bar 10 by again tightening the clamp-screw 11.

The base 1, standard 2, arm 3 and head 4 are preferably formed as a single casting, the base 15 being in the nature of an inverted pan closed at the bottom by a plate 15 and gasket 16. The standard 2 is provided with a vertically arranged chamber 17 within which operates a belt 18 adapted to transmit rotary motion from a pulley 19, secured to the main shaft 5, to a similar pulley 20 secured upon the rear end of a shaft 21 journaled horizontally in bearings 22 and 23 provided by the base 1. To the unbroken upper surface 1^a of the base 1 there is secured a horizontally disposed work-supporting plate 24, one end of which is formed to receive the standard 2.

The end 21^a of the shaft 21, remote from the pulley 20, projects through a bore 25 formed in the vertical end wall 1^b of the base 1, and carries a conventional chain-stitch loop-taker 26 which cooperates with the needle 9 in the formation of stitches. Thus, rotation of the main shaft 5 effects reciprocation of the needle-bar and the needle carried thereby, and also, through the belt 18 and pulleys 19 and 20, effects rotation of the loop-taker 26 in timed relation with the reciprocations of the needle.

Cooperating with the presser-foot to effect step-by-step movements of the work between successive reciprocations of the needle, is a feeding mechanism including a feed-dog 27 which operates through a slot 28 in a throat-plate 29 secured in the work-plate 24. This feed-dog is adapted to be given backward-and-forward and rising-and-falling movements such as are common in conventional four-motioned feeding mechanisms. Power to effect these movements is taken from the shaft 21 by mechanism located wholly within an oil-tight chamber 30 formed by the inverted pan-like base 1 and the bottom plate 15.

As shown most clearly in Figs. 3 and 4, the feed-dog 27 is secured upon one end of a feed-bar 31 by a screw 32 and held against turning 55

relative thereto by having its shank 27^a fitted into a slot 33^a formed in a disk 33. The disk 33 is secured to a head 31^a formed integral with the feed-bar. The feed-bar 31 is journaled in a 5 bore 35 in a horizontally disposed sleeve 36 formed integral with a depending rod 37. The rod 37 is slidingly mounted in a vertically arranged bearing sleeve 38 forming a part of an oscillatory feed-rocker 39. This feed-rocker is 10 journaled upon a shaft 40 mounted in bushings 41 secured in the base 1. Formed integrally with the feed-rocker 39 is a slotted segmental arm 42 adapted to have operatively connected thereto, by a stud 42^a, the lower end of a pitman 43 having its upper end 43^a embracing a crank or eccentric portion 44 formed on the shaft 21. A portion of the stud 42^a is fitted within a slot 42^b in the arm 42. Thus rotation of the shaft 21 will, through the elements 44, 43, 42, effect oscillation of the feed-rocker 39 and thereby cause 15 the feed-bar 31 and the feed-dog 27 carried thereby, to move back and forth transversely of the base 1, thus giving to the feed-dog its feed-and-return strokes.

25 The amplitude of movement transmitted to the feed-dog from the crank 44 is dependent upon the point of connection of the pitman 43 and stud 42^a with the segmental arm 42. This point may be shifted, thereby to vary the stroke of the 30 feed-dog, by the manipulation of a feed-adjusting lever 45 pivoted upon a screw 46 at the right end of the machine (as viewed in Fig. 1) and projecting through a slot 47 formed in the forward wall of the standard 2 (see Fig. 2). Intermediate its ends, the lever 45 is connected by a link 48 to an arm 49 secured upon the rear end of a rock-shaft 50, journaled in the base 1 parallel to the shaft 21. At its opposite end the shaft 50 carries an arm 51 which is connected, 35 by a link 52, to the stud 42^a which connects the pitman 43 to the segmental arm 42. It will be apparent that shifting of the lever 45 will vary the position of the stud 42^a in the slot in the segmental arm 42 and thereby vary the feeding 40 stroke transmitted to the feed-dog. The lever 45 may be secured in its various positions of adjustment by a clamp-screw 53 threaded upon the projecting end 45^a of the lever 45 and adapted to engage a slotted cover-plate 54 secured upon 45 the front face of the standard 2.

Rising and falling movements are transmitted to the feed-bar, in timed relation with its backward and forward movements, by a crank or eccentric portion 55 also provided by the shaft 21 (see Figs. 3 and 6). This crank is embraced by a block 56 having a bore 57 slidingly receiving one end of a bar 58. The other end of the bar 58 is slidingly mounted in a sleeve 59, pivoted, by means of a trunnion 60, in a bearing block 61 secured in the end-wall 1^b of the base 1. Intermediate its ends the bar 58 is formed with an enlarged portion or clamp-block 62 having a transverse bore 63 adapted to receive the feed-bar 31 which is held against endwise movement therein 55 by a set-screw 64 (see Figs. 4 and 6). The block 62 is split, as at 65 and a clamp-screw 66 serves to draw the opposite sides together thereby to firmly grasp the feed-bar 31 therein. As the feed-rocker 39 is oscillated about the shaft 40 60 to give the feed-dog its feed-and-return movements, the bar 58 slides back and forth in the block 56 and the sleeve 59. Rotation of the crank 55 with the shaft 21 causes the bar 58 to be oscillated about the axis of the trunnion 60 and as 65 the clamp-block 62, carried by the bar, embraces

the feed-bar 31 it causes that element, and the feed-dog carried thereby, to be moved up and down, successively into and out of engagement with the work held upon the work-plate 24 by the presser-foot 12.

Thus it will be apparent that the mechanism above described will give to the feed-bar 31 and the feed-dog 27 backward-and-forward and rising-and-falling movements such as are common to so-called four-motioned feeding mechanisms.

As shown most clearly in Figs. 3 and 4, the feed-bar 31 extends through an opening 68 formed in the end-wall 1^b of the base 1. This opening is of sufficient size to permit the feed-bar to have the necessary vertical and horizontal movements 15 to give the feed-dog 27 the usual rising-and-falling and backward-and-forward movements common to four-motion feeding mechanisms.

In this type of feeding mechanism it is highly desirable that the work-engaging face of the 20 feed-dog be maintained parallel with the work-supporting surface of the throat-plate during the entire feeding stroke of the feed-dog. That result has been attained in the present construction by merely arranging the bar 58 at an inclination 25 relative to the work-supporting surface of the throat-plate 29 and work-plate 24, as seen most clearly in Fig. 6. With this construction, as the feed-dog is moved from front to rear to advance the work, its tendency to drop, after the 30 feed-lift eccentric has passed through its uppermost position, is counteracted by the rising movement of the inclined bar 58 as it slides upwardly in the block 56 and sleeve 59.

To lighten the load on the feed-driving mechanism and to eliminate vibration in the machine, the feed-rocker has been balanced by means of a counterweight 67 attached thereto at the side of the axis of the rocker opposite the segmental arm 42. This counterweight statically 40 balances the feed-rocker and therefore very little power is required to give to it its rocking movements. Likewise, during the running of the machine, the reactionary forces transmitted to the bearings (which forces heretofore have set up vibrations in sewing machines) are counteracted or neutralized with the result that the present machine may be operated at high speed with little or no vibration.

Having thus set forth the nature of the invention 50 what I claim herein is:

1. A feeding mechanism for sewing machines comprising a drive shaft, a feed-rocker journaled on an axis substantially parallel to said drive shaft, a horizontally disposed feed-bar slidingly connected to said feed-rocker and arranged substantially parallel to said drive shaft, a feed-dog carried by said feed-bar and arranged transversely thereof, means to rock said feed-rocker thereby to give to the feed-dog its feed and return movements, and means actuated by said drive shaft to effect vertical sliding movements of said feed-bar relative to said feed-rocker thereby to give the feed-dog rising and falling movements.

2. A feeding mechanism for sewing machines comprising a rotary shaft, an oscillating feed-rocker journaled on an axis substantially parallel to said shaft, and provided with an upright bearing sleeve; a pin slidingly mounted in said sleeve 70 and provided, at one end, with a transverse sleeve portion, a feed-bar mounted in said sleeve portion and arranged substantially parallel to said shaft, a feed-dog carried by said feed-bar and arranged transversely thereof, means actuated by 75

5 said shaft to rock said feed-rocker thereby to give to the feed-dog its feed and return movements, and means to move said feed-bar vertically thereby to give to the feed-dog rising and falling movements.

10 3. A feeding mechanism for sewing machines comprising a shaft, a feed-rocker journaled on an axis substantially parallel to said shaft, a member carried by said feed-rocker and having a pin-and-sleeve connection therewith to permit of vertical movements of said member on said feed-rocker, a feed-bar pivotally carried by said member and arranged substantially parallel to said shaft, a head on one end of said feed-bar, a feed-dog secured to said head and arranged transversely of said feed-bar, means to rock said feed-rocker thereby to give to the feed-dog its feed and return movements, and other means actuated by said shaft to give to said member, 15 feed-bar and feed-dog rising and falling movements.

20 4. In a sewing machine having a frame provided with an aperture in one wall thereof, a feeding mechanism comprising a shaft, a feed-rocker journaled in said frame, a feed-bar carried by said feed-rocker and arranged substantially parallel to the axis of said feed-rocker, a portion of said feed-bar projecting through the aperture in said frame, a feed-dog carried by said feed-bar and arranged transversely thereof, a first means within said frame and actuated from said shaft to rock said feed-rocker thereby to give to the feed-dog its feed and return movements, a second means actuated from said shaft to give to the feed-dog rising and falling movements, and auxiliary means for giving a rising movement to said feed-bar during a portion of the time said second means is tending to lower the feed-bar.

25 5. A feeding mechanism as set forth in claim 4, in which the auxiliary feed-bar lifting means comprises an inclined bar slidably mounted on the sewing machine frame and having an operative connection with said feed-bar and with said feed-rocker, whereby movement of the feed-rocker in one direction causes said slide-bar and feed-bar to be moved upwardly and rearwardly of the machine frame.

30 6. A feeding mechanism for sewing machines having a frame, comprising a feed-rocker pivot-

ally mounted on said frame and having an arm arranged transverse to the axis of the pivot, a feed-dog connected with said feed-rocker and adapted to be given backward and forward movements thereby, means acting on said arm at one side of said pivot for giving to said feed-rocker oscillatory movements, and a counterweight connected to said feed-rocker at the opposite side of said pivot for counter-balancing the weight of said arm.

10 7. A feeding mechanism for sewing machines having a frame, comprising a rotary shaft journaled in said frame, a feed-rocker pivotally mounted on said frame and having an arm extending transverse to the axis of the pivot, a feed-bar extending lengthwise of said shaft, a feed-dog connected with said feed-bar, a pin-and-sleeve connection between said feed-bar and said feed-rocker, means actuated by said shaft and engaging said arm for oscillating said feed-rocker to give to said feed-bar and feed-dog backward-and-forward movements, and means actuated by said shaft to give to said feed-bar and feed-dog rising-and-falling movements relative to said feed-rocker.

15 8. A feeding mechanism for sewing machines as set forth in claim 7 in which a counterweight is attached to said feed-rocker at the opposite side of the pivot thereof from which said arm extends.

20 9. A feeding mechanism for sewing machines having a frame, comprising a rotary shaft journaled in said frame, a feed-bar, a feed-dog secured thereto, means actuated by said shaft for giving to said feed-bar backward-and-forward movements, a rotary eccentric actuated by said shaft for giving to said feed-bar rising-and-falling movements, and auxiliary means acting on said feed-bar to give to it a rising movement at the time when said eccentric initiates the downward movement of the feed-bar.

25 10. A feeding mechanism for sewing machines as set forth in claim 9, in which the auxiliary means for giving to the feed-bar a rising movement comprises an inclined slideway up which said feed-bar is moved during the forward movement thereof.

RUDOLPH BECKER.
